UNITED STATES PATENT OFFICE.

BYRON B. CARTER, OF HINSDALE, ILLINOIS, ASSIGNOR TO CHARLES D. ALLAN, OF CHICAGO, ILLINOIS.

FIRE-EXTINGUISHER.

1,401,135.

Specification of Letters Patent. Patented Dec. 27, 1921.

Application filed June 29, 1916. Serial No. 106,606.

To all whom it may concern:

Be it known that I, BYRON B. CARTER, a citizen of the United States, and a resident of Hinsdale, in the county of Du Page and 5 State of Illinois, have invented a certain new and useful Improvement in Fire-Extinguishers, of which the following is a specification.

This invention relates to fire extinguishers, and relates particularly to sprinklers for automatic sprinkler systems.

The primary object of the invention is to provide an improved fusible element for such sprinklers which, in addition to the 15 requisites of strength and sensitiveness to heat, shall be safe and dependable in use, so that they will not break under the stresses to which they are subjected until fused in the manner intended. To this end, 20 a fusible element of my invention comprises the various features and details of construction hereinafter described and claimed.

In the accompanying drawing, in which 25 my invention is fully illustrated,

Figure 1 is a perspective view of a 30 sprinkler having a fusible element of my invention.

Fig. 2 is an enlarged front or face view of the side of the element which is exposed 35 in Fig. 1.

Fig. 3 is an enlarged side view of said 40 element.

Fig. 4 is a sectional view of said element on the line 4—4 of Fig. 2; and

Fig. 5 is a sectional view thereof on the 45 line 5—5 of Fig. 4.

Referring now to the drawing, A designates, as a whole, the frame of the sprinkler. Said frame A may be of any desired or ap- 50 proved construction and will be readily understood by those familiar with the art from the drawing without a detailed description thereof.

As shown, the sprinkler is of the type in 55 which the fusible element, designated as a whole *a*, is applied to secure the cap 1 in position to close the nozzle of said sprinkler, by means of what may appropriately and for purposes of convenient reference be 60 called toggle levers, respectively designated 2 and 3, the relation being such that, in use, said fusible element will be under compression. My improved fusible element may, however, be used in other usual and well

known ways and I do not, therefore, desire 55 to limit myself to the manner of use shown.

My improved fusible element consists of only two members 4 and 5, which are made of suitable metal, being preferably stamped from sheet phosphor bronze and being of 60 proper width and thickness to afford requisite strength, not only in the metal itself, but in the solder joint by which said members are connected.

For purposes of convenient reference and 65 to distinguish between them, the member 4 will be hereinafter referred to as the upper member and the strut member 5 as the lower member.

The lower end of the upper member 4 70 rests on a shoulder 6 formed on the lower member 5 at a distance from the end thereof which overlaps said member 4. The position of the shoulder 6 is such that said members will overlap to such an extent and said 75 members are made of such width as will provide a solder joint connecting said members, of sufficient area to insure adequate strength in said fusible element. In practice, I contemplate a solder joint substantially five-eighths of an inch long and eleven-sixteenths of an inch wide.

The shoulder 6 will sustain the entire 80 compression stress to which said strut is subjected in use and is offset from the line 85 of thrust or compression of said fusible element to produce a lateral component tending to break the solder joint between the overlapping ends of said members by a turning movement thereof relatively to each 90 other about the point of contact of the overlapping end of the member 4 with the shoulder 6.

To insure against breaking of the member 95 5 at the shoulder 6 under any load to which it may be subjected in use, said shoulder is preferably reinforced and strengthened by a rib 7 formed by stamping back the central portion of said member below the shoulder 6, as clearly shown in the drawing.

Formed on one of said members are marginal flanges 8 which are adapted to embrace the lateral edges of the other member, the relation being such that said flanges will operate as guides to insure alinement 100 of said members with each other with the shoulder 6 on the member 5 and the end of the member 4 designed to bear against said

shoulder, parallel with each other, whereby a metal to metal contact between said shoulder and the end of said member 4, which bears against said shoulder, may be conveniently secured in soldering said members together, thereby effectually preventing relative movement of said members in use due to the load to which they are subjected, with attendant cold flow of the solder and consequent weakening of the solder joint. As shown, said flanges 8 are formed on the upper member 4 and embrace the lateral edges of the member 5 above the shoulder 6. Said flanges 8 will form a channel on the side of the member 4 which contacts with the member 5, which is slightly wider at the bottom thereof than the width of the member 5 and the sides of which, formed by said flanges 8, flare slightly outwardly away from the surface of the member 4 on which they are formed, thus effectually insuring against wedging and binding of the member 5 in said channel, that is, between said flanges 8. In what I now consider the preferable relation, the bottom of the channel formed by said flanges 8 is made one sixty-fourth of an inch wider than the member 5 and said flanges 8 are each flared approximately three degrees from a perpendicular to the plane of the side of said member 4 on which said flanges are formed.

As is generally well known by persons familiar with the use of automatic sprinklers under different conditions, the solder joints connecting the members of fusible elements, if exposed to the action of certain acid fumes, as the fumes of nitric and hydrochloric acid, will be attacked thereby, causing the solder to set and harden and also raising the fusing point thereof, thus rendering the sprinklers very unreliable and uncertain in their operation. To overcome this objectionable feature, resort is usually had to what is technically known as "loading," which may be described as surplus solder applied to the exposed edges of the solder joints and which forms a body of solder of such thickness that it will effectually protect the solder joints proper from the action of the acid fumes, thus insuring fusing of the fusible element and the collapse of the sprinkler at the predetermined temperature desired.

In my improved sprinkler, the flanges 8 provide convenient means for very effectually loading the solder joint connecting the members 4 and 5. For this purpose, said flanges 8 are made continuous and of such length that they will cover the edges of the solder joint between the overlapping ends of the members 4 and 5 from the shoulder 6 to a point above or beyond the overlapping end of the member 5, and are preferably made of such width that they will ex-

tend slightly above the exposed side of the overlapping end of said member 5, all as clearly shown in Fig. 4 of the drawing. To load the solder joint between the overlapping ends of the members of the fusible element, the spaces between the edges of the member 5 and the flanges 8 are filled with solder, a sufficient quantity of solder being used to form what may be called beads 9 on said fusible element *a* overlying the edges of the solder-filled spaces between said member 5 and the flanges 8, said beads being made of such size that they will afford full protection to the solder joints at the margins of said fusible elements. At the overlapping ends of the lower member 5, the solder joint between said members is protected by solder fillets 10, best shown in Fig. 4, in the angle between the overlapping end of said member 5 and the adjacent side of the member 4. In Fig. 1 of the drawings, the loading is not shown at all; in Figs. 2 to 4, inclusive, it is indicated in dotted lines to avoid obscuring parts overlaid thereby; and in Fig. 5 the loading 9 is shown in full lines.

I claim:

1. A fusible element comprising overlapping members soldered together, a shoulder formed on one of said members against which the overlapping end of the other member bears, flanges on one of said members which embrace the lateral edges of the other member constructed and arranged to support said members in alinement with each other, and loading for the solder joint connecting said members comprising solder which fills the spaces between said flanges and the lateral edges of the member embraced thereby, substantially as described. 105

2. A fusible element comprising overlapping members soldered together, a shoulder formed on one of said members against which the overlapping end of the other member bears, flanges on one of said members which embrace the lateral edges of the other member and which extend above the exposed surface thereof, constructed and arranged to support said members in alinement with each other, and loading for the solder joint connecting said members comprising solder which fills the spaces between said flanges and the lateral edges of the member embraced thereby and which also forms beads which cover said spaces, substantially as described. 110

3. A fusible element comprising overlapping members soldered together, a shoulder formed on one of said members against which the overlapping end of the other member bears, flanges on one of said members which embrace the lateral edges of the other member and which flare outwardly, said flanges being constructed and arranged to support said members in alinement with 125 130

each other, and loading for the solder joint connecting said members comprising solder which fills the spaces between said flanges and the lateral edges of the member em-
5 braced thereby, substantially as described.

4. A fusible element comprising overlapping members soldered together, a shoulder formed on one of said members against which the overlapping end of the other
10 bears, and flanges on one of said members which embrace the lateral edges of the other member, said flanges being constructed and arranged to support said members in alinement with each other, substantially as de-
15 scribed.

5. A fusible element comprising overlapping members soldered together, a shoulder formed on one of said members against which the overlapping end of the other
20 member bears, flanges on the member the end of which bears against said shoulder which embrace the lateral edges of said shouldered member, said flanges being constructed and arranged to support said mem-
25 bers in alinement with each other, substan-
tially as described.

6. A fusible element comprising overlapping members soldered together, a shoulder formed on one of said members against
30 which the overlapping end of the other member bears, flanges on the member the end of which bears against said shoulder

which embrace the lateral edges of said shouldered member, said flanges being constructed and arranged to support said mem-
35 bers in alinement with each other, and load-
ing for the solder joint connecting said members comprising solder which fills the spaces between said flanges and the lateral edges of said shouldered member, substan-
40 tially as described.

7. A fusible element comprising overlapping members soldered together, a shoulder formed on one of said members against which the overlapping end of the other
45 member bears, and flared flanges on the member the end of which bears against said shoulder which embrace the lateral edges of said shouldered member, said flanges being constructed and arranged to support said
50 members in alinement with each other, and loading for the solder joint connecting said members comprising solder which fills the spaces between said flanges and the lateral edges of said shouldered member, substan-
55 tially as described.

In testimony, that I claim the foregoing as my invention I affix my signature in the presence of two subscribing witnesses this 23 day of June, 1916.
